METHOD OF AND MEANS FOR PREPARING
PARISONS

John K. E. Diffenderffer, Baltimore, Md.

Application November 24, 1933, Serial No. 699,621

8 Claims. (Cl. 49—9)

This invention relates to the art of manufacturing glass bottles and the like and is more particularly an improvement in the method of shaping glass parisons and to a mechanism whereby the shaping can be effected automatically.

In the art of making bottles with a gob feed machine the gob is of an elongated substantially cylindrical shape and the blank mold should be as near the same shape as possible because of difficulties in properly filling or loading an angular blank. While a cylindrical blank is correct for use in the production of round or nearly round bottles, it has been found that when these cylindrical blanks are expanded in a blow mold to form a bottle which is angular in shape, a poor distribution of the glass takes place with the result that the walls become thin at the corners or ends of the bottle and the bottle produced is not of sufficient strength to meet the requirements. This poor distribution of the glass also prevents proper annealing of the bottle because different strains are set up during the cooling operation where the glass is of different thicknesses and this is a difficulty which is almost impossible to correct.

The present invention is designed to partially re-shape a blank while it is being transferred to the blow mold, the re-shaping being such as to bring the parison more nearly to the shape of the blow mold than would be the case otherwise.

It is also an object to re-shape the blank while being transferred and without retarding the operation of the machine so that the capacity of the machine will not be reduced.

Another object is to so shape the parison during the transfer operation that after it has been placed in a blow mold designed to produce a bottle which is square, oblong, or of other angular configuration, the said parison when blown, will produce a bottle or the like the walls of which will be of substantially uniform thickness and strength and can be annealed in a satisfactory manner.

With the foregoing and other objects in view which will appear as the description proceeds, the invention consists of certain novel details of construction and combinations of parts and in certain steps of the method hereinafter more fully described and pointed out in the claims, it being understood that changes may be made in the construction and arrangement of parts and in the disclosed method without departing from the spirit of the invention as claimed.

It is to be understood that the present improvements can be used in connection with any type

of bottle machine or the like wherein a parison is transferred from a blank mold to a blow mold. This transfer may be made by lifting the parison from the blank mold and carrying it upwardly in an arc to a blow mold or the parison could be transferred in a right line direction or horizontally in a circular motion. In other words the present improvements are not restricted to any particular type of machine but can be employed wherever a transfer of the parison is made.

In the accompanying drawings a portion of one type of bottle machine has been illustrated.

In said drawings:

Figure 1 is a plan view of a blank mold, a blow mold, and a vertically swinging transfer mechanism with which is combined the structural arrangement forming a part of the present invention, the said mechanism being illustrated in an intermediate position and showing a parison being shaped.

Figure 2 is a front elevation of the structure illustrated in Figure 1.

Figure 3 is a side elevation.

Figure 4 is a section on line 4—4, Figure 1.

Figure 5 is a plan view on a reduced scale showing the transfer and shaping mechanism in their initial positions.

Figure 6 is a similar view showing the position of these parts during the transfer of the parison and immediately prior to the shaping of the parison.

Figure 7 is a view similar to Figures 5 and 6 showing the positions of the parts after the parison has been shaped as shown in Figures 1 and 2 but prior to being deposited in the blow mold.

Figure 8 is a view similar to Figure 7 showing the positions of the parts after the parison has been deposited in the blow mold.

Figure 9 is an enlarged side elevation of one of the cams forming a part of the shaping mechanism.

Figure 10 is an elevation of the inner member of the lost motion connection between the shaping mechanism and its operating shaft, said shaft being shown in section and the spring forming a part of the connection being shown in position.

Figure 11 is an elevation showing the inner side of the outer member of the lost motion connection.

Figure 12 is a view showing a parison in section positioned between the presser heads prior to the shaping operation.

Figure 13 is a similar view showing the positions of these parts upon the completion of the shaping operation.

Figure 14 is a horizontal section through the blow mold and showing the shaped parison positioned therein prior to the final blowing operation.

5 In illustrating the mechanism of the glass blowing machine only essential parts have been shown. These include a blank mold 1, a blow mold 2 and any mechanism necessary to open and close these molds at the proper times. As 10 this mechanism does not constitute any part of the present invention it has not been deemed necessary to show or describe it.

A bearing structure 3 is mounted on the machine between the two molds and journaled in 15 this structure is a shaft 4 which is adapted to be rotated back and forth by any suitable means in properly timed relation to the opening and closing of the molds. For example a gear 5 can be secured to this shaft and can be rotated by a rack 6 20 mounted for up and down movement.

Extending from the shaft 4 is a transfer member 7 having the usual neck ring 8 for engaging the neck portion of a formed blank and transferring the parison from the blank mold after it has 25 been opened to the blow mold. This transfer mechanism can be of any of the well-known construction capable of opening and closing and as it constitutes in itself no part of the present invention it has not been shown or described in 30 detail.

Secured to each side of the bearing structure 3 is a plate 9 through which the terminals of shaft 4 extend and each of these plates is provided on its outer side face with an arcuate cam 10. Secured to each terminal of shaft 4 is a disk 11 which, as shown in Figure 10, has a semi-circular groove 12 in one face concentric with the shaft and providing abutments 13 at the ends of the groove. Blocks 14 are slidably mounted in the 40 groove and are held normally pressed against the abutments 13 by an arcuate coiled spring 15 which is seated in groove 12 and thrusts against the blocks.

Mounted to rotate on end portions of shaft 4 45 are disks 16 each of which has an arcuate groove 17 in its inner side corresponding with groove 12 and normally registering therewith. Both grooves 12 and 17 are substantially semi-circular in transverse contour and as the blocks 14 and spring 15 50 are circular in transverse contour they will be movably seated in both grooves, as will be apparent by referring to Figure 4.

Extending from each of the disks 16 is an arm 18 and a bracket 19 is extended outwardly from 55 each of these disks. Each bracket has a transverse bearing pin 20 on which is journaled a lever 21 the lower arm of which is normally spaced from arm 18 by a spring 22. A roller 23 is carried by the upper arm of lever 21 and is adapted to 60 ride along cam 10.

Pivots connected to the upper end of lever 21 is an arm 24 the outer end of which is joined to bracket 19 by a link 25. Thus a parallelogram is produced which maintains arm 24 at the same 65 angle under all conditions.

Arm 24 has a terminal lug 26 at its inner end in which is seated a stem 27 extending from a yoke 28. The stem is adjustably mounted and is adapted to be held against movement relative to 70 lug 26, by a set screw 29.

The yokes 28 carried by the two stems 27 are extended toward each other and mounted in each of the yokes is an ear 30 projecting from a presser head 31 which can be in the form of a flat plate. 75 These plates can be adjusted angularly about

their connections with the yokes 28, as will be obvious.

The arm 18 extends between and cooperates with adjustable stops 32 carried by the respective plates 9. Thus the roller 23 is maintained in 5 contact with the cam 10 at all times.

In operation back and forth rotation is imparted to shaft 4 in timed relation to the opening and closing of blank mold 1 and blow mold 2. Normally the transfer mechanism is in an up-standing position as shown by full lines in Figures 1 to 4 inclusive and at this time the presser heads 31 are thrust toward each other by the action of springs 22 which force the rollers 23 into the recessed intermediate portions of cams 10. 10 While the parts are thus located the grooves 12 and 17 are in accurate register with the blocks 14 15 in contact with the respective ends of both grooves.

When shaft 4 is rotated in one direction 20 to move the transfer mechanism toward the blank mold, the blocks 14 will act as keys for transferring motion from disks 11 to disks 16 so that levers 21 and arms 24 will thus be shifted relative to plates 9 and rollers 23 will be caused 25 to ride out of the central recessed portions of cams 10. Thus heads 31 will be moved apart under the action of the cams. Heads 31 will move with the transfer structure 7 until arms 18 come into contact with those stops 32 in the paths 30 thereof. At that time further rotation of disks 16 will be stopped but disks 11 will continue to rotate with shaft 4 and each will thrust against one of the blocks 14 and compress its spring 15 against the other block 14 which, during this 35 operation, will be held back by the end wall of the groove 17 in disk 16. Compression of springs 15 will continue until the transfer mechanism arrives with the neck ring under the blank mold. With the parts thus located as shown for example 40 in Figure 5 and by broken lines at the right of Figure 3, the gob is deposited in the blank mold and subjected to its initial shaping in the usual way. Thereafter, at the proper time, the blank mold is opened and shaft 4 is actuated to move 45 the transfer mechanism away from the blank mold, carrying the parison P with it. During the first part of this movement of the transfer mechanism the disks 11 will rotate independently of disks 16 while the springs 15 are assuming 50 their normal positions in the two grooves 12 and 17. As soon as such positions are assumed the advancing blocks 14 in the two disks 11 will come against the adjacent end walls of grooves 17 and exert a thrust against disks 16 so as to cause 55 them to rotate with disks 11. Consequently disks 16 and the parison shaping mechanism carried thereby will be moved with and at the same speed as the transfer mechanism through a short arc determined by the distance between the stops 60 32. During this joint movement of the transfer and shaping mechanisms the rollers 23 will travel along their respective cams 10 and enter the intermediate recessed portions of the cams so that springs 22 will momentarily force the presser 65 heads 31 toward each other and against the parison. Consequently the parison which initially had been cylindrical or nearly so as shown in Figure 12 will be flattened out by the presser heads as illustrated in Figure 13.

Immediately following the flattening operation described, the arms 18 will come against the other stops 32 which are in the paths thereof. This will not take place however until after the rollers 23 have moved out of the recessed por- 75

tions of the cams and caused the presser heads 31 to move apart out of contact with the flattened parison.

When the rotation of disks 16 is stopped following the foregoing operation the disks 11 will continue to rotate with shaft 4, causing those blocks 14 in one end of each groove 12 to compress the springs 15 against the other blocks 14 which are held back by the adjacent ends of the restrained disks 16. This movement of the disks 11 and the transfer structure 7 independently of the shaping structure will continue until the neck ring 8 is brought to position upon the blow mold 2 which at that time will close about the flattened parison P as shown in Figure 14. The final operation then takes place and as the parison has been flattened out so as to conform nearly to the configuration of the cavity in the blow mold, the resultant bottle will be of substantially uniform strength because of the equal distribution of glass throughout the walls thereof.

Following the formation of the bottle the transfer mechanism moves back toward the blank mold and the operation just described is then repeated.

Importance is attached to the fact that the parison shaping mechanism moves with the transfer mechanism and that the shaping operation occurs during this movement. Thus there is no delay in the operation of the machine and capacity will not be reduced. Furthermore as the parts move in unison there will be no drag set up upon the parison but a direct inward pressure will be produced and the texture of the glass will not be marred.

What is claimed is:

1. The method of forming angular bottles or the like which includes the step of pressing the sides of the unconfined suspended parison toward each other, while being transferred from a blank mold to a blow mold without retarding the movement of the parison.

2. The method of forming angular bottles or the like which includes the steps of forming a round blank, transferring the parison with a single movement to an angular blow mold, and momentarily compressing the sides of the parison during such movement.

3. The method of forming an angular bottle

or the like from a rounded parison which includes the step of pressing the sides of the unconfined suspended parison while being transferred and without retarding its transfer thereby to conform it more closely to the shape of the finished article. 5

4. In a glass bottle machine, a blank mold, a blow mold, a structure movable to transfer a parison, and means movable with and at the same speed as the transfer structure for imparting momentary compression to the sides of the 10 parison during its transfer.

5. In a glass bottle machine a blank mold, a blow mold, a structure movable to transfer a parison, a parison shaping mechanism, means for automatically picking up the shaping mech- 15 anism for travel with the transfer structure during a portion of the movement thereof and means controlled by the movement of said mechanism for momentarily compressing the sides of the parison while being transferred. 20

6. In a glass bottle machine a blank mold, a blow mold, a structure movable to transfer a parison, parison pressing members at opposite sides of the path of said structure, means for carrying the members with the structure during 25 a portion of the movement thereof, and means for automatically shifting the members toward and from each other during said movement thereby to flatten a parison therebetween while being transferred. 30

7. In a glass bottle machine a blank mold, a blow mold, a structure working therebetween and movable to transfer a parison, a parison shaping mechanism, a lost motion connection between the transfer structure and the shaping mecha- 35 nism for producing a joint movement thereof during an intermediate portion of the movement of the transfer structure, and means for actuating the shaping mechanism during said joint movement to flatten the parison while being 40 transferred.

8. In a glass bottle machine a blank mold, a blow mold, means for transferring a parison with a single movement from the blank mold to the blow mold, and means movable with the trans- 45 fer means during a portion of its movement for pressing the sides of the parison toward each other.

JOHN K. E. DIFFENDERFFER.
